(57) **CLAIM**

We claim the ornamental design of a belt loop purse, as shown and described.

DESCRIPTION

FIG. 1 is a left, front perspective view of a belt loop purse;

FIG. 2 is a top plan view of a belt loop purse;

FIG. 3 is a front elevational view of a belt loop purse;

FIG. 4 is a rear elevational view of a belt loop purse;

FIG. 5 is a bottom plan view of a belt loop purse;

FIG. 6 is a left side elevational view of a belt loop purse; and,

FIG. 7 is a right side elevational view of a belt loop purse.

The surface shading represents the surface of the belt loop purse.
